SWAG LAMP

Charles W. Lindquist, P.O. Box 133, Harvey, Ill. 60426

Filed Dec. 18, 1974, Ser. No. 533,873

Term of patent 7 years

Int. Cl. D26—05

U.S. Cl. D48—23 R

FIG. 1

FIG. 1 is perspective view from above of a swag lamp showing my new design.

FIG. 2 is a perspective view of the lamp taken from a position slightly below the lamp.

The broken lines are shown in FIGS. 1 and 2 for illustrative purposes only.

I claim:

The ornamental design for a swag lamp, as shown and described.
